(57) **CLAIM**

The ornamental design for a motor vehicle, toy, and/or replicas thereof, as shown and described.

DESCRIPTION

FIG. 1 is a front and left side perspective view of a motor vehicle, toy, and/or replicas thereof showing our new design; FIG. 2 is a top, front, and left side perspective view thereof; FIG. 3 is a rear and left side perspective view thereof; FIG. 4 is a front elevation view thereof; FIG. 5 is a rear elevation view thereof;

FIG. 6 is a right side elevation view thereof; and,

FIG. 7 is a top plan view thereof.

The broken lines in the drawings illustrate portions of the motor vehicle, toy, and/or replicas thereof that form no part of the claimed design.

1 Claim, 7 Drawing Sheets
